UNITED STATES PATENT OFFICE.

MARQUIS F. SEELEY, OF FREMONT, NEBRASKA.

GRAIN-ELEVATOR.

SPECIFICATION forming part of Letters Patent No. 336,755, dated February 23, 1886.

Application filed June 13, 1885. Serial No. 168,575. (No model.)

To all whom it may concern:

Be it known that I, MARQUIS F. SEELEY, of Fremont, in the county of Dodge and State of Nebraska, have invented certain new and

5 useful Improvements in Grain-Elevators; and I do hereby declare that the following is a full, clear, and exact description thereof, reference being had to the accompanying drawings, and to the letters of reference marked 10 thereon, which form a part of this specification.

In a prior patent, No. 288,371, granted to the present applicant upon the 18th day of November, 1883, a structure for handling and 15 storing grain is shown, having a unitary upper structure, forming its bottom, arranged to slope from the sides of the building toward its center, and forming the bottoms of a series of storage-bins extending to the roof, and of receiving and other bins placed under a working-floor in the central part of the building, the bins mentioned being therein shown as 20 constructed to discharge their contents at the lower end of the two elevator-belts extending to the top of the building. As shown in said 25 patent, also, the elevators are provided with casings or legs which are continuous from the top to the bottom of the building, and which form the supporting-frame from which the 30 several operative parts immediately connected with the elevator-belts are mounted.

The present invention relates to improvements in the construction of elevators of the class shown in said patent, and also to other 35 improvements in elevators, as will hereinafter appear.

The invention consists in the matter hereinafter described, and pointed out in the appended claims.

40 The invention may be more readily understood by reference, to the accompanying drawings, in which—

Figure 1 is a sectional plan view of an elevator-building constructed in accordance with 45 my invention, taken upon line $x-x$ of Fig. 2. Fig. 2 is a vertical section of the lower part of the building, taken upon the indirect line $x-x$ of Fig. 1. Fig. 3 is an enlarged detail section through the lower end of the elevator casing 50 or legs. Fig. 4 is a detail section of a modified form of the parts adjacent to the inlet-opening of the elevator. Fig. 5 is a detail perspective

view illustrating the casing for connecting the exit-opening of one of the bins with the corn-sheller shown in Figs. 1 and 2. Fig. 6 is a 55 plan view of the same.

In the particular construction illustrated in the drawings, A A are the outside walls of the building. B B are two transverse parallel partitions therein; and C C are storage-bins located between the end walls of the building and the said partitions, and formed by radially-arranged partitions, c c c, the bottom of said bins being, as shown, inclined downwardly 60 from the outer walls of the building toward a 65 point at the middle of said partitions.

D D are two elevator-belts inclosed in boxes, legs, or casings D' D', and located at their lower end in a pit or depression, C³, located below the level of the discharge-openings c of the 70 bins C, and at a little distance laterally therefrom. The grain discharged from the said 75 openings is delivered into the said pit by means of an inclined surface, C², which is located between the partitions B B, and slopes from the wall of the building to the said pit, the grain falling upon the said surface being directed to the lower end of the elevator-casings by means of inclined guides c², as clearly 80 shown in Fig. 1 of the drawings. The elevator-belts pass at their lower ends over the usual pulleys, d d, having suitable bearings at the lower ends of the casing D', as shown.

E is a working-floor, which is placed between the partitions B B. 85

F is a driveway on the level with the floor, by means of which grain may be brought into the building; and G G are lower compartments or receiving-bins into which grain may be discharged through a suitable aperture, f, in the 90 floor of the driveway. The receiving-bins G G have a common inclined bottom, G¹, which slopes to the pit C³, before mentioned, and they are separated by a central vertical partition, G². At the lower end of the bins G are 95 discharge-gates g, arranged opposite the inlet-openings in the elevator-boxes D', whereby grain may be permitted to pass from said bins to the elevator. A bin, I, for cleaned grain, is located upon the upper portion of the inclined surface C² and adapted to discharge 100 upon the lower portion of said surface, as fully set forth in the said patent.

The features of the device above described

are constructed and operate generally in the manner set forth in the said prior patent.

As an improvement in grain-elevators, applicable to those of the character above described, and also to other elevating devices for grain, I provide an exhaust-fan, J, or other air-exhausting device, and connect said fan by means of air trunks or ducts K with the passage by which grain is delivered to the 10 casing of the elevator, whereby air may be drawn forcibly from the said passage, and the light impurities thereby separated from the grain before the latter passes to the elevator-buckets.

15 In the particular construction herein shown the discharge-opening g of the receiving-bins G are connected with the opening d', by which the grain enters the casing, by means of a short spout or passage, K', to which the air-trunk 20 K is connected at a point adjacent to the casing of the elevator.

The exhaust-fan J may be actuated in any desired manner, said fan in the construction illustrated being driven by means of an engine, L, located upon the floor E of the building.

By the use of the exhaust-fan connected in the manner described the grain, in case it contains a relatively small quantity of light 30 impurities, may be sufficiently cleaned to render any other cleaning unnecessary, and when the passage of the grain through a cleaning-machine is necessary, by such preliminary cleaning the amount of work to be done by the 35 said machine is greatly decreased.

It will be observed that the inlet-opening of the air-duct K is located adjacent to the point where the grain is taken into the elevator-buckets, and the grain being shaken or stirred 40 up by the action of the said buckets, the action of the air-current in taking up the light impurities from the grain is greatly facilitated.

A slightly different and preferred construction in the parts is illustrated in Fig. 4, in 45 which the passage K' is provided with an aperture, k, which may be covered with wire-cloth or other perforate material, as shown, and which preferably communicates with the open air by means of a duct, K², or otherwise, 50 so that an air-current may be caused to pass transversely through the grain within the passage K', and thereby more thoroughly remove the light impurities from the latter.

The advantages existing in the use of the 55 exhaust-fan and the connections shown for removing the light impurities from the grain before its delivery to the elevating device of the elevators may obviously be obtained by means other than those shown, and my invention is not, therefore, as it relates to the devices mentioned, restricted to the particular means shown, but said devices, in connection with an elevating device, are broadly herein claimed.

As heretofore made, the elevator legs or 65 casing D', forming the supporting-frame of the operating parts of the elevator, have been attached to the upper edge of and constructed

to rest upon a cast-metal casing or shoe, within which the grain is delivered and from which it is removed by the scoops or buckets of the 70 elevator. This construction has the obvious disadvantage of bringing the entire weight of the upper part of the elevator upon the said casting, and the latter has been necessarily made of objectionable thickness and weight in 75 order to withstand the strain thus caused.

As an improved construction in the parts mentioned, I extend the side pieces, d', of the casing D', downwardly outside of the shoe D' to a suitable supporting-piece or foundation, 80 D³, placed below the shoe. By this means the downward pressure due to the weight of the upper parts of the elevating device is transmitted directly through the side pieces of the legs to the foundation D³, and the casing or 85 shoe is therefore unaffected by the downward thrust of the latter. The said shoe, in the particular construction herein shown, is constructed of sheet metal with vertical side plates, d², secured upon the inner face of the side pieces, 90 d', of the casings, said side plates, d², being connected by a curved plate, D⁴, forming the bottom of the casing.

As a further improvement in elevator buildings of the character shown in said patent, 95 the upper part of one of the receiving bins or compartments G is divided from the lower part thereof by means of an inclined partition, G³, so as to form a bin or hopper, G⁴, more especially intended for corn in the ear, said bin 100 being constructed to discharge at its lower end into a corn-sheller, M, located upon the inclined surface G' and adapted to discharge into the lower part of the hopper G.

A preferred means for supporting the corn-sheller is herein shown, in which the lower beams, M', of the sheller-frames are inclined at the same angle as the floor or surface G', so that the said corn-sheller may rest and be secured upon the said floor, and the making of 110 a separate horizontal foundation for the corn-sheller is thereby rendered unnecessary.

The hopper G⁴, herein shown, embodies novel features of construction at its part adjacent to its exit-opening, whereby liability 115 of the latter becoming stopped or choked by the wedging or "bridging over" of the ear-corn or other large material between the opposite walls of the hopper is practically obviated. For this purpose the said hopper is, as 120 clearly shown in Figs. 2, 3, and 6, provided at two adjacent sides of its exit-opening with vertical walls N, the walls G⁵ G⁶ of the hopper opposed to the said walls N being inclined downwardly to the said exit-opening in 125 the usual manner. The vertical walls N in usual cases extend about a foot or a foot and a half above the lower margins of the opposite walls G⁵ G⁶, the inclined walls G³ and G⁴ of the bin being constructed to slope to the upper 130 edges of the said vertical wall in an obvious manner.

In the operation of the hopper constructed as above described the ears adjacent to the

vertical walls will obviously move or slide by gravity freely downwardly upon the latter, and the catching or wedging of the said ears will therefore seldom if ever occur.

5 An improved construction in means for connecting wooden hopper-walls with the metal casing of the corn-sheller, whereby a simple and convenient construction of the parts is obtained, is illustrated in connection with the hopper G^4 shown, and is as follows: To the inlet-opening m of the sheller M , as more clearly shown in Fig. 5, is secured a metal casting, N' , adapted for attachment by bolts or otherwise to the margins of the inlet-opening thereof, said casting being rectangular in plan, and provided at two of its sides with vertical parts N^2 , extending above the horizontal parts N^3 of the casting, and forming the vertical walls N of the hopper.

20 In constructing the wooden parts of the hopper of the casing above described two of the inclined walls of the hopper, as $G^5 G^6$, Fig. 2, are constructed to slope downwardly to and are connected at their lower margins with the lower horizontal parts of the casting N' , and the two opposite walls $G^3 G^7$ are connected at their lower edges with the upper edge of the vertical parts N' of said casting.

In constructing the wooden parts of a hopper by the use of a casting, N' , as described, the two triangular spaces (one of which is indicated at g^2 , Figs. 2, 5, and 6) at the vertical sides or edges of the wall N' may be filled by a triangular piece of plank, or by triangular extensions cast upon the walls N' .

35 The construction of the parts mentioned will be made more clear by examination of the perspective view, Fig. 6, in which the parts of the hopper nearest the eye are indicated by dotted lines.

The novel features of construction in the hopper herein shown and above described form the subject of another application for patent, Serial No. 168,574, filed by me upon the 45 13th day of June, 1885, in which application said hopper is broadly claimed. Said novel features of construction in the hopper are, however, also herein claimed as applied to a structure for storing grain.

50 In practice the inlet-aperture of the sheller and the casting are made square in plan, so that the latter may be placed upon the sheller with the walls N' in any position found desirable.

55 In Figs. 1 and 2 of the drawings the floor of the driveway F above the receiving-bins G and G^4 , with a dumping device consisting of pivoted timbers O , located at the sides of the opening f , and adapted to receive the wheels 60 of a wagon and to be tilted with said wagon, so as to discharge the load into the said opening f , which is provided with a door or flap, f' , which is closed to permit the passage of horses over it. As an improvement in such 65 dumping device, whereby the wheels of a wagon passing into the driveway may be readily guided into proper position upon the

dump-timbers, curved guide-strips O^2 are secured upon the floor of the driveway in position suitable for the purpose, as clearly 70 shown in Fig. 1. In connection with the said guide-strips O^2 longitudinal guide-strips O' may be employed to hold the wheels properly in place in passing over and while resting upon the dump-timbers. The guide-strips O' , 75 as herein shown, are attached to the dump-timbers themselves; but as far as the operation of the guide-strips O^2 is concerned said guide-strips O' may be otherwise attached, as found desirable or convenient.

80 Other guide-strips, O^3 , are preferably secured upon the floor at the end of the dump-timbers, from which the wheels pass, so that in case the wagon is driven too far over the timbers the front wheels will be held in place 85 when backing the wagon into its proper position upon the timbers.

I claim as my invention—

1. In a building for storing grain, the combination, with an elevator and storage and receiving bins, of an exhaust-fan or equivalent device applied to remove the light impurities from the grain in its passage from the receiving-bin to the elevating devices of the elevator, substantially as described.

90 2. In a building for storing grain, the combination, with an elevator and a receiving-bin, of a passage connecting the receiving-bin with the lower end of the elevator-casing, an exhaust-fan, and an air-duct connecting the fan with the said passage, whereby light impurities may be removed from the grain before its delivery to the elevating devices of the elevator, substantially as described.

95 3. The combination, with an elevator and a receiving-bin, of a passage for grain connecting the receiving-bin with the lower end of the elevator-casing, and an exhaust-fan communicating with said passage, the latter being provided with an air-inlet opening or openings at 100 a point opposite the opening leading to the fan, whereby a current of air may be drawn through the grain in said passage, substantially as described.

105 4. In a building for storing grain, the combination, with an elevator and a metal shoe for the lower pulley of said elevator, of a foundation for the elevator, said elevator having the lower ends of its legs or casings extended downwardly past the said shoe to the 110 foundation, and constructed to rest upon the latter, substantially as described.

115 5. In a building for storing grain, the combination, with the elevating devices and storage-bins, of a receiving-bin, G^4 , for ear-corn, 120 and a corn-sheller, M , connected with the discharge-opening of the said bin G^4 , and constructed to discharge to the lower end of the elevating devices, substantially as described.

125 6. In a building for storing grain provided with elevating devices, an inclined or hopper bottom sloping toward the lower end of the elevating devices, and a working-floor, E , of a receiving-bin, G^4 , located beneath the work-

- ing-floor, and a corn-sheller, M, located upon the said hopper-bottom beneath the said receiving-bin G⁴, substantially as and for the purpose set forth.
- 5 7. In a building for storing grain, the combination, with an elevator and an inclined surface or floor, G', sloping downwardly to the inlet-opening of the elevator, of a corn-sheller having the lower timbers of its supporting-frame inclined to correspond with the inclination of said floor or surface, substantially as and for the purpose set forth.
- 10 8. In a building for storing grain, a hopper provided in its part adjacent to its exit-opening with opposite vertical and inclined walls, substantially as described.
- 15 9. In a building for storing grain, the combination of a corn-sheller and a hopper discharging into the corn-sheller, and provided 20 in its part adjacent to its exit-opening with two vertical walls, and having its walls opposite said vertical walls inclined, substantially as described.
- 25 10. In a building for storing grain, the combination, with a corn-sheller, M, and the wood- en walls of a hopper, G⁴, of a metal casting, N, provided with vertical side walls, N', substantially as described.
11. The combination, with a driveway-floor and pivoted dump-timbers, of guide-strips O², 30 secured to said floor, substantially as described.
12. The combination, with a driveway-floor and pivoted dump-timbers O, provided with guide-strips O', of guide-strips O², secured to the said floor, substantially as described. 35
13. The combination, with the floor of the driveway, and pivoted dump-timbers O, of guide-strips O², secured to the said floor at one end of the dump-timbers, and other guide-strips, O³, secured to the said floor at the opposite end of said timbers, substantially as described. 40

In testimony that I claim the foregoing as my invention I affix my signature in presence of two witnesses.

MARQUIS F. SEELEY.
